CLAIM

We claim the ornamental design for a bottle cap, as shown and described.

DESCRIPTION

FIG. 1 is a top perspective view of a bottle cap showing our new design;

FIG. 2 is a bottom perspective view thereof;

FIG. 3 is a top view thereof;

FIG. 4 is a front view thereof;

FIG. 5 is a bottom view thereof; and,

FIG. 6 is a sectional view thereof taken in the direction of line 6-6 in FIG. 3.

The rear view, the right side view, and the left side view of the bottle cap shown in FIGS. 1-6 are each identical to the front view shown in FIG. 4.

1 Claim, 2 Drawing Sheets
